UNITED STATES PATENT OFFICE.

CHARLES GOLDTHWAIT, OF SOUTH WEYMOUTH, MASSACHUSETTS.

BOOT-BLACKING APPARATUS.

SPECIFICATION forming part of Letters Patent No. 249,336, dated November 8, 1881.

Application filed March 19, 1881. (Model.)

To all whom it may concern:

Be it known that I, CHARLES GOLDTHWAIT, of South Weymouth, in the county of Norfolk and State of Massachusetts, have invented a new Improvement in Apparatus for Blacking and Polishing Boots and Shoes, of which the following is a full, clear, and exact description.

My invention consists in a novel construction and arrangement of a box or case and devices connected therewith, whereby provision is made for carrying a box of blacking, a brush for applying the same, and a polishing-brush, as hereinafter more particularly described.

In the accompanying drawings, Figure 1 is a top view of the box or case, partly broken away, with the polishing-brush removed. Fig. 2 is a longitudinal vertical section, with the polishing-brush in place in the box or case.

A represents a polishing-brush of the ordinary construction and form. It may be provided with a handle, *a*, or not, as may be preferred.

B represents a box or case, of elliptical or other suitable form corresponding with the shape of the brush, and of a depth considerably greater than the length of the bristles on the brush A. On two opposite sides of the interior of the box or case B are two abutments, *b*, against which rests a bar, C, thus dividing the lower part of the box into two semi-elliptical compartments, *d d'*. In the compartment *d* is a circular box of blacking, E, which rests on the bottom of the case B, and is held steadily in place by bearing against the bar C on one side, and by a packing, *f*, of cork or other suitable material, on the other side, and between it and the end of the casing. The compartment *d* is provided with a removable cover consisting of a semi-elliptical plate, G, provided with a ring, *g*, or other device for lifting it. This plate or cover lies flat on the

top of the blacking-box E and forms a cover for the same, and is held in place by the abutments A.

For applying the blacking I prefer a long-handled brush, H, such as is used for paint or paste. The handle of this brush may be flat, or it may be a round handle with a flat surface formed on it by cutting away a portion, as shown.

When the apparatus is not in use the cover G is placed over the blacking-box E, the brush H lies with its handle on the top of the cover G, and its brush portion in the compartment *d'*, and the polishing-brush A is inserted in the case B so that its bristles bear on the brush H sufficiently to hold it in place, while the back of said brush A fits in the top of the case B and forms a cover for the same, and is held in place therein by a pin or stud, *i*, at one end and a screw, J, at the other end.

The screw J may be a thumb-screw, so that it may be readily removed and replaced without a screw-driver.

Having thus described my invention, what I claim as new, and desire to secure by Letters Patent, is—

1. The blacking-box case B, having on opposite sides the abutments *b b*, the box-compartment *d*, with flat cover G, the bar C, between said compartment and abutments, the apartment *d'*, adapted to receive the brush while its handle rests on the cover G, and an upper chamber or space adapted to receive and be covered by the polishing-brush, as shown and described.

2. The combination, with a blacking-box, E, of a case having the opposite abutments *b b*, the bar C, and packing *f*, to hold said box firmly in one end of the case, as described.

CHARLES GOLDTHWAIT.
